CLAIM

The ornamental design for a control lever for boats and ships, as shown and described.

DESCRIPTION

FIG. 1 is a perspective view of an embodiment of a control lever for boats and ships of the present disclosure;

FIG. 2 is a top view thereof;

FIG. 3 is a front view thereof;

FIG. 4 is a side view thereof; and,

FIG. 5 is a bottom view thereof.

The broken lines in the drawings illustrate portions of the control lever for boats and ships that form no part of the claimed design.

1 Claim, 5 Drawing Sheets
